CLAIM

The ornamental design for a lawn mower blade sharpener, as shown and described.

DESCRIPTION

FIG. 1 is a front perspective view of a lawn mower blade sharpener, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and

FIG. 9 is a perspective view showing the lawn mower blade sharpener in a use state thereof; and,

FIG. 10 is an enlarged detail view of area 10 in FIG. 2. The broken lines in the drawings illustrate the portions of the lawn mower blade sharpener, which form no part of the claimed design.

The dash-dot-dash broken lines encircling the enlarged views are for annotative purposes only and form no part of the claim thereof.
